UNITED STATES PATENT OFFICE.

WILLIAM S. O'BRIEN, OF SAN FRANCISCO, CALIFORNIA.

DESIGN FOR A CANE.

SPECIFICATION forming part of Design No. 22,451, dated May 23, 1893.

Application filed March 6, 1893. Serial No. 464,905. Term of patent 3½ years.

To all whom it may concern:

Be it known that I, WILLIAM S. O'BRIEN, a citizen of the United States, residing at San Francisco, in the county of San Francisco and State of California, have invented a certain new and original Design for Cane and Umbrella Handles, of which the following is a specification.

My design is for the handles of canes and umbrellas, and the leading feature thereof is the novel shape, outline or configuration of the handle, as illustrated in the accompanying drawings, in which—

Figure 1 is a side view of a cane or umbrella handle provided with my design. Fig. 2 is a front end view thereof.

The upper end of the stick portion, *a*, of the handle is rounded, as shown at 2, and thereon are represented portions of the continents and seas of the earth's surface. The head or hand piece, 3, is shaped to have the appearance of the hull of a vessel, and it is

connected with the end, *a*, of the stick, at one end only, and projects to one side of the stick at substantially a right angle thereto. At 4 ²⁵ the stick portion of the handle is roughened to give the appearance of water. A chain appears to issue from a hawse-hole near one end of the vessel and carries at its end an anchor which is fastened into one of the land masses represented on the end of the stick. ³⁰

The handle when seen from the front, as shown in Fig. 2, shows one end of the vessel as cutting into the rounded end, *a*, with the representation of the water between them. ³⁵

What I claim is—

The design for the handle of a cane, substantially as shown and described.

In testimony whereof I affix my signature in presence of two witnesses.

WILLIAM S. O'BRIEN.
